MOBILE BRICKMAKING MACHINE

Dino A. Morelli, Pasadena, and Benjamin Pinsker, Hollywood, Calif.; said Morelli assignor to said Pinsker

Application January 30, 1953, Serial No. 334,218

6 Claims. (Cl. 25—2)

Our invention relates generally to brickmaking equipment and more particularly to mobile equipment adapted to perform the entire brickmaking process within one complete unit, the only step of the process not completed therein being that of curing.

Brickmaking has been practiced from earliest times, but despite its age and widespread use, relatively few improvements have been made in the process since it was first practiced. Within the past few centuries, power operated machinery has been used to mix the materials going into the production of bricks, and bricks have been formed by extrusion, rather than by simple molding. As a protection against weathering and aging, many bricks are now baked by firing in a kiln, since the material of which some bricks are formed is easily eroded. However, many bricks are presently made in substantially the same manner as bricks were made thousands of years ago.

In some instances, bricks are merely baked in the sun, and when made of the proper materials, have withstood the elements for several centuries. An example of the lasting qualities of such bricks is found in the adobe buildings erected hundreds of years ago in the southwestern United States, Mexico, and Central and South America. However, erosion of such bricks by the elements still occurs, and relatively recently such bricks have been formed of a clay or adobe mixed with a bituminous emulsion to produce a brick that, when cured, is substantially waterproof.

As mentioned, these adobe bricks must be cured or allowed to dry, and while they do not require firing in a kiln, they must be stacked so that they can dry. Since this requires a period of several days, the problem of providing sufficient space becomes a serious one if commercial operations are to be economically conducted.

It often happens that the demand for adobe bricks does not warrant the establishment of a permanent brickmaking plant, and because of the size and weight of such bricks, it is not economically feasible to ship them a great distance.

It is therefore a major object of our invention to provide a mobile brickmaking machine capable of being moved from place to place and adapted to produce finished adobe bricks.

Another object of our invention is to provide such a machine in which the entire operation, from the digging or excavation of the clay or other material to the delivery of the completed brick to the curing area is accomplished by the one machine.

It is a further object of our invention to provide a brickmaking machine of this general type in which the various steps in the manufacture of bricks may be under the control of an operator at all times.

Still another object of our invention is to provide a machine, that, in addition to excavating the raw material, provides a graded surface on which the completed bricks may be placed for curing.

It is a still further object of our invention to provide

2

such a machine that is relatively simple in operation and comparatively inexpensive in cost.

These and other objects and advantages of our invention will become apparent from the following description 5 of a preferred form thereof, and from the drawing illustrating that form, in which:

Figure 1 is a side elevational view, showing the left side of a mobile brickmaking machine, the machine being in the position it occupies when in the process of making 10 bricks;

Figure 2 is a side elevational view of the left side of the machine, but showing the machine in the position it occupies when being transported from place to place;

Figure 3 is a rear elevational view of the device, partially broken away, as it appears when in the process of cutting or grading the land and making bricks;

Figure 4 is a side elevational view of the left or hoisting 20 side of the device, to a somewhat larger scale than Figures 1 and 2, and partially broken away to show the interrelationship of the various elements;

Figure 5 is a side elevational view of the opposite side of the device from that shown in Figure 4, this view also being partially broken away to show the construction and arrangement of various parts;

Figure 6 is an end view of the excavating and mixing equipment taken in the direction of the arrow 6 in Figure 5 and partially broken away to show the relationship of various members;

Figure 7 is a cross-sectional view taken on the line 7—7 30 of Figure 4 and showing the interior of the pug mill and the extrusion screw;

Figure 8 is a cross-sectional view taken on the line 8—8 of Figure 6 and showing the cooperative relationship between the transfer screw and the hammer mill; and

Figure 9 is a top plan view of the brickmaking machine, with parts broken away to show a relationship of the 35 various members.

Referring now to the drawings and particularly to Figures 1, 3, and 9, the numeral 20 indicates generally 40 a mobile excavating, mixing, and extrusion apparatus adapted to be mounted upon a truck or similar vehicle 21 for movement both from area to area, and also about a given area during the process of manufacturing bricks. Broadly, the brickmaking machine includes excavating 45 equipment, here shown as a rotating helix or screw 22, adapted to loosen earth and move it to one side of the equipment where it is picked up by a conveyer, here shown as a bucket conveyer 23, and raised to the top of the equipment. After the excavated earth is discharged 50 from the bucket conveyer 23, it is carried by a transfer screw conveyer 24 to a hammer mill 25 from which it drops, in crushed form into a pug mill 26. Within the pug mill 26, the crushed and powdered earth is mixed with a bituminous emulsion supplied from a reservoir or 55 tank 27 mounted upon the truck 21 and the resulting mixture is discharged into an extrusion screw conveyor 30. The extrusion screw 30 carries the mixture to an opening 31 adapted to receive a discharge nozzle, where the material is given the final desired shape, and may 60 thereafter be cut into the desired lengths. When so cut, the resulting bricks are placed upon the ground to dry and cure, the ground previously having been smoothed and leveled by the passage of the equipment 20 and the action of the excavator screw 22.

65 In this way, a minimum amount of labor is required for the production of bricks. Since excavation, mixing, and extrusion is accomplished by one compact mobile unit, a minimum of space is required for this unit, and since 70 the ground is leveled and smoothed by the apparatus, a curing and drying area is automatically provided. The equipment has the further advantage, that, being mobile,

it can be moved into an area where the demand would not justify the erection of permanent facilities, and where the cost of shipping bricks from established yards is too great to be economically feasible.

Turning now to a more detailed description of the apparatus, our mobile brickmaking apparatus 20 is adapted to be mounted on the rear of a more or less conventional truck 21 that may be modified as hereinafter specified. The rear wheels 32 of the truck, preferably dual wheels because of the load they must carry, are mounted a short distance forward of the rear of the frame 33, and the tank 27, carrying the bituminous emulsion, is mounted between the rear wheels 32 and the cab 34, as is conventional.

It will be appreciated that when the truck 21 is being moved from one area to another, it will normally travel at speeds comparable to those of trucks of similar size when traveling on the highway. However, when the truck 21 acts to pull or tow the brickmaking equipment 20 while the latter is in the process of making bricks, the forward speed of the truck is, of necessity, greatly reduced. To provide for this slower or creeping movement, we prefer to modify the drive connections of the truck so that both fast and slow forward speeds are readily available, and that at the same time, provide a power take-off or connection for operating the brickmaking machinery 20.

As is customary, the truck 21 is provided with a drive or power shaft 35 and a differential (not shown) between the rear wheels 32. However, instead of connecting the drive shaft directly to the differential, we prefer to connect the drive shaft to a transfer mechanism 36 which in turn is connected by a shaft 37 to the differential, and then to the wheels 32. The transfer mechanism 36 also has other shafts connected to it, and one of these, shaft 38, is used as a power take-off for the brickmaking equipment 20, as hereinafter described. Another shaft 40 projects from the transfer mechanism 36, and this shaft, like the drive shaft 35, may be used to drive the output shaft 37 to move the truck 21 forward.

The shaft 40 acts as a power input shaft to the transfer mechanism 36 for very slow forward speeds, and it is driven by suitable means, such as a hydraulic motor 41. The hydraulic motor is operated by fluid under pressure, provided by a hydraulic pump (not shown) which in turn is driven by the engine of the truck 21. The advantage, of course, of the hydraulic motor 41 is that it may be used to drive the truck 21 forward more slowly, and also that it may have a characteristic that may be likened to resilience, since when some obstruction is encountered, the hydraulic motor 41 will stop without causing any damage to itself, the hydraulic system, or the stalled members. A rigid mechanical coupling does not have this resilience.

The transfer mechanism 36 also includes suitable means such as a clutch operated by a handle 42 so that when the clutch is engaged, the drive shaft 40, connected to the hydraulic motor or other low speed drive, also drives the power take-off shaft 38. Thus, the rear wheels 32 of the truck 21 may be driven either in the conventional manner by means of the drive shaft 35, whereby the truck may be moved at comparatively high speed, or power may be delivered from the low speed source 41, through the drive shaft 40 so that the truck, in effect, creeps. Under the latter conditions, power is also delivered to the brickmaking equipment 20.

The equipment 20 is mounted between the sides of the truck frame 33 and is pivotally supported at its forward end for limited rotation about an axle 43 parallel to the rear axle of the truck 21. The lower limiting position of the equipment 20 is determined by studs 45 that project from the side of the equipment and are adapted to rest in blocks 46 mounted upon the sides of the frame 33. Near the rear of that frame, we provide an upwardly extending framework 47 that straddles the equipment 20 and carries hoisting means such as a block 48 to which there is attached a chain 50 that is connected to some suitable

point on the equipment 20. By operating the hoist 48, the equipment 20 may be pivoted about the axle 43 and raised from its operating position, indicated in Figure 1, to its traveling position indicated in Figure 2.

Along one side of the brickmaking equipment 20, there is a main power shaft 51 which extends in a direction generally parallel to the length of the truck 21. The shaft 51 is considerably above the transfer mechanism 36, and the power take-off shaft 38 which is connected to the main power shaft 51 is provided with universal joints or other suitable couplings 52 and 53 at each end. Also the take-off shaft 38 is preferably made extensible, as by a spline and sleeve construction 54, so that the overall length of the shaft may be varied, as is necessary when the brickmaking equipment 20 is moved from its operating to its raised or traveling position.

As best seen in Figure 5, the main power shaft 51 extends substantially the entire length of the equipment assembly 20 and carries a chain sprocket 55 near its forward end. A chain 56 engages both the sprocket 55 and another chain sprocket 57 to drive the latter which is mounted upon a shaft 58 extending from a gear box 60. Mounted on the shaft 58 within the gear box 60 is a bevel gear 61 that transmits power to a meshing gear 62 that in turn drives a shaft 63 extending across the equipment assembly 20, in a direction generally perpendicular to the main power shaft 51.

The shaft 63 carries the transfer screw conveyor 24, as best seen in Figure 9, and at its opposite end, remote from the gear 62, the shaft 63 carries a pair of sprockets 64 and 65. The sprocket 64 is relatively small, and carries a chain 66 that in turn drives a relatively large sprocket 67 carried by a shaft 70. The shaft 70 is carried by a vertically movable block 71 whose position may be changed by suitable means, such as a threaded rod and nut 72. The shaft 70 carries the upper sprocket wheel 73 for the bucket line conveyor 23, and the relative size of the sprocket wheels 64 and 67 insure that there will be ample power, though at a rather low speed, to raise the earth picked up by the buckets of the conveyor.

At its lower end, the bucket line conveyor 23 passes around a lower sprocket 74 that is mounted on a shaft 75, and this shaft continues across the width of the equipment assembly 20, carrying the worm or screw-type scraper 22. The shafts 63, 70, and 75, all rotate in a counter-clockwise direction, as seen in Figure 4, and thus the rear side of the bucket chain conveyor moves upwardly while the forward side moves downwardly. As previously mentioned, the shaft 75 carries the worm or screw-type scraper or excavator 22, and the helix into which the blade thereof is shaped so that as the shaft 75 rotates in a counter-clockwise direction, as seen in Figure 4, the blade moves dirt in a direction across the equipment assembly 20 to the bucket line 23. Material from the entire length of the screw-type scraper 22 is thus delivered to the bucket line 23, which takes this material, raises it, and deposits it in a hopper indicated generally by the numeral 76 in Figure 4, and through the bottom of which extends the transfer screw 24. This transfer screw 24, as previously mentioned, is driven by the shaft 63 and its direction of rotation, counter-clockwise as shown in Figure 4, is such as to move the material from the hopper 76 across the width of the equipment assembly 20, toward the power shaft 51, to the pug mill 26.

However, not all of the earth that is raised by the bucket line 23 is powdered or in sufficiently small lumps, and consequently the material is run through a hammer mill 25 prior to its admittance into the pug mill 26. As is best seen in Figures 6, 8, and 9, the hammer mill 25 includes a shaft 80 having radially projecting arms 81 extending therefrom for rotation therewith. The shaft 80 carries a sprocket 82 driven by a chain 83, and this in turn is driven by a sprocket 84 mounted upon a shaft 85 that extends partially across the equipment assembly 20, to the rear of the bucket line 23. The opposite end of

shaft 85 carries a sprocket 86 driven by a chain 87 that engages the previously mentioned sprocket 65 mounted on the end of the shaft 63 carrying the transfer screw conveyer 24. The driving sprockets 65 and 84 are relatively large, and the driven sprockets 86 and 82 are relatively small so that the shaft 80 and the arms 81 rotate at a fairly high speed, as is desirable for a hammer mill.

Near the discharge end of the transfer screw conveyer 24, aligned with the pug mill 26, the casing of the screw conveyer is provided with a series of slots 90 through which powdered earth, brought up by the bucket line 23, may drop into the pug mill 26. Lumps of earth that are too large to fall through the openings 90 are crushed by the radially extending arms 81 of the hammer mills 25, these arms extending through the openings 90 and hitting against the lumps of earth. It is important, of course, that the admission of the arms 81 through the openings 90 be timed so that the arms do not strike the screw conveyer 24, since this would damage the arms and/or the conveyer screw. The conveyer screw 24, it 10 will be appreciated, makes a close fit with the housing therefor so that a certain grinding or crushing action takes place as the edges of the screw pass over the openings 90. The arms 81 of the hammer mill 25 aid in this crushing, and as a result, a finely crushed and ground powder is dropped into the pug mill 26.

The purpose of the pug mill is to mix the powdered earth from the transfer screw 24 and hammer mill 25, with the bituminous emulsion supplied from the tank 27 mounted upon the truck 21. The mixing operation must be thorough and complete so that a homogenous product is obtained, and the mixing is accomplished by a series of arms or paddles 91 that are attached to and rotate with a shaft 92 extending the length of the pug mill 26. The shaft 92 carries at its rear end a sprocket 93 that is driven by a chain 94 which in turn is in engagement with a sprocket 95 mounted upon the rear end of the main power shaft 51. This arrangement, best seen in Figure 5, provides for power to be delivered at the rear end of shaft 92, and by a proper selection of the size of the sprockets 93 and 95, the shaft 92 is driven at a slower speed than the main power shaft 51.

In addition to mixing the bituminous emulsion with the powdered earth, the paddles 91 of the pug mill 26 also act to move the mixture toward the rear end of the pug mill, and this is accomplished by turning the paddles 91 so that their forward faces are at an angle to their plane of rotation. The paddles 91 thus act, to a certain extent, as a screw conveyer in addition to providing the necessary mixing action.

At the rear end of the pug mill 26 the case or housing 96 thereof is provided with an opening 97 that communicates with the housing of the extrusion screw conveyer 30. The housing 100 of the screw conveyer 30 extends rearwardly from the pug mill 26, and the passage-way 97 opens into the front of the housing 100 so that the mixture of dirt and emulsion is delivered to the extrusion screw at the forward end thereof, and forced by the latter to the rear of the housing 100 where it is ejected through the opening 31. The extrusion screw 30 includes a shaft 101 having a helical flange or worm 102 thereon, and the shaft is driven at its forward end by a chain 103 that engages sprockets 104 and 105 mounted upon the forward ends of the shafts 101 and 92, respectively.

After its discharge through the opening 31 at the rear of the extrusion screw 30, the mixture of powdered earth and bituminous emulsion may be given any desired shape by a nozzle (not shown) of the conventional type attached to the housing 100 of the extrusion screw or otherwise suitably supported, with the extruded material thereafter being cut to the desired length by suitable means 106 of more or less conventional type. Such forming nozzles and cutting means are well-known in the art, and we do not claim them in and of themselves.

as our invention, since any of a number of suitable types may be used.

When the extruded material is cut to the desired length, a brick 107 is thereby formed which is then deposited upon the ground behind the brickmaking equipment 20, which has been leveled by the operation of the excavating or grading worm 22. A partial housing or shoe 110 is located rearwardly of the grading worm 22, and is provided with a generally horizontally extending flange 111 that acts as a smoothing member to further smooth and level the surface of the ground that has previously been cut by the grading screw 22. The partial housing 110 also acts to insure that the major portion of the dirt loosened by the grading screw 22 will be moved by the latter to the bucket line conveyer 23 so that maximum efficiency is obtained.

The bricks formed by the machine and laid upon the ground in back of the machine are allowed to cure or dry for several days, the exact length of time depending upon the moisture content of the freshly extruded brick, the weather conditions during the time of curing and other factors. During the curing process, however, the brickmaking machine may be moved to another location, or, depending upon the number of bricks desired and the size of the area that is to be graded or surfaced for the manufacture of bricks, the equipment may continue its operations in other portions of the same area.

After the bricks have been cured, they are removed from the ground and used for their intended purpose. If 30 desired, the brickmaking equipment may then be passed over the area previously graded to again remove dirt from the surface of that area for the manufacture of more bricks.

When the requisite number of bricks have been produced, the brickmaking apparatus 20 may be hoisted, by means of the block 48, from the operating position, shown in Figure 1, to the traveling position shown in Figure 2. The power transfer mechanism 36 is then operated so that the rear wheels of the truck 21 are driven in a substantially conventional manner, at higher speeds than are possible when the brickmaking apparatus 20 is in operation, and the entire combination may be moved over the usual public highways to a new location.

From the foregoing, it will be seen that we have described a mobile brickmaking apparatus fully capable of achieving the objects and securing the advantages heretofore enumerated. It will be apparent that changes may be made therein by those skilled in the art, such changes not departing from the novel features of our invention as defined herein. Consequently, while we have shown a preferred form of our invention, we do not wish to be restricted to the particular form or arrangement of parts herein shown and described, except as limited by our claims.

We claim:

1. A brickmaking of the class described which includes: a self-powered vehicle having a power take-off; a surface excavator adapted to remove dirt from the exposed surface of the earth; smoothing means cooperating with said surface excavator to smooth the earth behind said surface excavator; hoisting means adapted to raise the dirt loosened by said surface excavator; pulverizing means operable to powder the dirt raised by said hoisting means; mixing means positioned to receive the gravity discharge from said pulverizing means and mix it with a wetting material; extrusion means receiving the mixture of said dirt and said wetting material from said mixing means and discharging it at a point located rearwardly of said surface excavator and said smoothing means and adjacent said smoothed earth; and means connecting said excavator, hoisting means, pulverizing means, mixing means, and extrusion means to said power take-off for driving thereby while said vehicle is moving forward.
2. A brickmaking machine of the class described which

includes: a self-powered vehicle having a power take-off; a surface excavator adapted to remove dirt from the exposed surface of the earth; smoothing means located rearwardly of said excavator and bearing against said surface of the ground, said smoothing means and said excavator cooperating to smooth and somewhat compact the earth behind said excavator; a bucket line hoisting means located at one end of said excavator and operable to raise the dirt loosened by said excavator; pulverizing means positioned to receive the dirt raised by said hoisting means and acting to powder said dirt; tank means mounted on said vehicle and adapted to contain a wetting material for mixing with said dirt; mixing means positioned to receive said wetting material from said tank means and the gravity discharge from said pulverizing means and mix said powdered dirt and said wetting material; extrusion means receiving the mixture of said dirt and said wetting material from said mixing means and discharging it at a point located rearwardly of said surface excavator and said smoothing means and adjacent said smoothed earth; and means connecting said excavator, hoisting means, pulverizing means, mixing means, and extrusion means to said power take-off for driving thereby while said vehicle is moving forward.

3. A brickmaking machine of the class described which includes: a self-powered vehicle having a power take-off; a screw-type surface excavator positioned to bear against the exposed surface of the ground rearwardly of the major portion of said vehicle, and operable to loosen dirt from said surface and move it to one end of said excavator; smoothing means located rearwardly of said excavator and bearing against said surface of the ground, said smoothing means and said excavator cooperating to smooth and somewhat compact the earth behind said excavator; a bucket line hoisting means located at one end of said excavator and operable to raise the dirt loosened by said excavator; pulverizing means positioned to receive the dirt raised by said hoisting means and acting to powder said dirt; tank means mounted on said vehicle and adapted to contain a wetting material for mixing with said dirt; mixing means positioned to receive said wetting material from said tank means and the gravity discharge from said pulverizing means and mix said powdered dirt and said wetting material; screw-type extrusion means positioned to receive the mixture of said dirt and said wetting material from said mixing means and operable to compress said mixture and discharge it in compressed form at a point located rearwardly of said surface excavator and said smoothing means and adjacent said smoothed earth; and means connecting said excavator, hoisting means, pulverizing means, mixing means, and extrusion means to said power take-off for driving thereby while said vehicle is moving forward.

4. A brickmaking machine of the class described which includes: a self-powered vehicle having a pivotable section at the rear thereof, said section being selectively movable between a raised or traveling position and a lowered or operating position; a power take-off mounted on said vehicle and selectively operable to deliver power to an auxiliary shaft from the power plant of said vehicle while said vehicle is moving; a screw-type surface excavator supported by said pivotable section and positioned to bear against the exposed surface of the ground rearwardly of the major portion of said vehicle when said section is in lowered position, and to be raised above the exposed surface of the ground when said section is in raised position, said excavator being operable to loosen dirt from said surface and move it to one end

of said excavator; smoothing means located rearwardly of said excavator and carried thereby to bear against said surface of the ground when said excavator is in lowered position, said smoothing means then cooperating with said excavator means to smooth and compress the earth behind said excavator; a bucket line hoisting means mounted on said pivotable section at one end of said excavator and operable to raise the dirt loosened by said excavator; pulverizing means carried by said pivotable section and positioned to receive the dirt raised by said hoisting means and acting to powder said dirt; tank means mounted on said vehicle and adapted to contain a wetting material for mixing with said dirt; mixing means located on said pivotable section and positioned to receive said wetting material from said tank means and the gravity discharge from said pulverizing means and mix said pulverized dirt and said wetting material; screw-type extrusion means carried by said pivotable section and connected to said mixing means to receive the discharge therefrom, said extrusion means acting to compress the mixture of dirt and wetting material and discharge it in compressed form at a point located rearwardly of said surface excavator and said smoothing means and adjacent said smoothed earth; and power transmission means extending from said power take-off and including said auxiliary shaft, and connected to said excavator means, said hoisting means, said pulverizing means, said mixing means, and said extrusion means for operating all of said means when said pivotable section is in lowered position and while said vehicle is moving.

5. A brickmaking machine of the class described which includes: a self-powered vehicle having a power take-off; a surface excavator mounted on said vehicle and adapted to remove dirt from the exposed surface of the earth; smoothing means located on said vehicle rearwardly of said excavator and adapted to smooth the exposed earth behind said surface excavator; mixing means; extrusion means adapted to discharge said dirt after it has been mixed, said discharge occurring adjacent said exposed and smoothed earth behind said surface excavator; and means connecting said excavator, mixing means, and extrusion means to said power take-off for operation thereby.

6. A brickmaking machine of the class described which includes: a self-powered vehicle having a power take-off; a surface excavator mounted on said vehicle and adapted to remove dirt from the exposed surface of the earth; smoothing means located on said vehicle rearwardly of said excavator and adapted to smooth the newly exposed surface of the earth behind said surface excavator; hoisting means adjacent said surface excavator and adapted to raise the dirt removed by said surface excavator; mixing means; extrusion means adapted to discharge said dirt after it has been mixed, said discharge occurring adjacent said exposed and smoothed earth behind said surface excavator; and means connecting said excavator, hoisting means, mixing means and extrusion means to said power take-off for operation thereby.
